* cited by examiner

Primary Examiner—T. Chase Nelson*Assistant Examiner*—Mark Cavanna(74) *Attorney, Agent, or Firm*—Kilyk & Bowersox, P.L.L.C.(57) **CLAIM**

A design for a drying device, as shown and described.

DESCRIPTION

FIG. 1 is a perspective view of the drying device showing my new design;

FIG. 2 is a top plan view thereof; and,

FIG. 3 is a side elevational view thereof.

The broken lines are included for the purpose of illustrating portions of the drying device that forms no part of the claimed design.
